UNITED STATES PATENT OFFICE.

WILLIAM E. BROCK, OF ELIZABETH, ASSIGNOR, BY DIRECT AND MESNE ASSIGNMENTS, TO MARTIN L. TRIMMER, OF DUNELLEN, N. J.

CAN-OPENER.

SPECIFICATION forming part of Letters Patent No. 264,818, dated September 19, 1882.

Application filed April 3, 1882. (No model.)

To all whom it may concern:

Be it known that I, WILLIAM E. BROCK, a citizen of the United States, residing at Elizabeth, in the county of Union and State of New Jersey, have invented certain new and useful Improvements in Can-Openers, of which the following is a specification, reference being had therein to the accompanying drawings.

My invention relates to an instrument for opening cans.

This invention consists in a novel construction, combination, and arrangement of a handle having a forked or slotted shank, a metal plate forming a blade or knife having a vertical flange or rib on one part and a stop on another, and fastening device, as hereinafter more fully set forth.

In the accompanying drawings, Figure 1 represents a perspective view. Fig. 2 is a back view, showing flange or rib and stop. Fig. 3 is a bottom view.

Similar letters represent corresponding parts.

The letter A represents a handle, which may be made of wood or any other suitable material. The lower end of the handle terminates in a shank, B, which is either provided with a slot extending its entire length or it is split longitudinally, so as to divide it into two branches, b b, which latter form is preferable.

C is a thin metal plate, approximately of a triangular form and preferably curved in cross-section, although it may be made straight, if necessary. The metal plate C is inserted in the slot or slit of the shank, extending downwardly therefrom, and it is secured in place by a screw, pin, rivet, or bolt, a, passing through it and through the branches b b.

On the lower part of the blade C is formed an oblique cutting edge or knife, d, the upper part ending in a stop, H, which stop H arrests the downward action of the blade.

On the blade C is formed a vertical flange or rib, E, which not only serves to strengthen the blade C, but more particularly forms a guiding-edge, which prevents the blade C from slipping backward, and acts as an abutment to force the oblique cutting edge or knife d forward through the material, thereby greatly facilitating the cutting operation. The flange or rib E is suitably curved or formed on its lower part (see a', Fig. 1) to provide for its facile insertion into the can.

In using the instrument, the blade C is inserted into the can by pressing on the handle A until it is arrested by the stop H and the shank B of the handle, when it is again withdrawn and again inserted in the can, which operation is continued as often as necessary to open the can, the flange or rib E forming an abutment or guiding-edge for every insertion of the blade after the first one.

The device is simple and cheap in construction, and affords a convenient opener for any style or size of can.

What I claim as new, and desire to secure by Letters Patent, is—

As an improved article of manufacture, a can-opener consisting of a handle, A, provided with a blade or knife, C, having a vertical guiding-edge, E, at right angles thereto, and an oblique cutting-edge, d, whereby provision is made in one instrument for opening different kinds of cans, substantially as described.

In testimony whereof I affix my signature in presence of two witnesses.

WILLIAM E. BROCK.
